(57) CLAIM

The ornamental design for a pair of footed dog leggings as shown and described.

DESCRIPTION

FIG. 1 is a top, front, left perspective view of a pair of footed dog leggings, showing my new design;

FIG. 2 is a bottom, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines depict portions of the pair of footed dog leggings that form no part of the claimed design.

1 Claim, 8 Drawing Sheets
